UNITED STATES PATENT OFFICE.

FREDERIC GEORGE JOHNSON AND ALFRED JOHNSON, OF HANLEY, COUNTY OF STAFFORD, ENGLAND.

LINK-PRESS FOR MAKING EARTHENWARE, &c.

SPECIFICATION forming part of Letters Patent No. 349,432, dated September 21, 1886.

Application filed July 13, 1886. Serial No. 207,870. (No model.) Patented in England March 31, 1885, No. 4,060.

To all whom it may concern:

Be it known that we, FREDERIC GEORGE JOHNSON and ALFRED JOHNSON, both subjects of the Queen of Great Britain, and residents 5 of Hanley, in the county of Stafford, England, have jointly invented certain Improvements in Link-Presses for Making Earthenware, &c., (for which we have been granted a patent in Great Britain, dated March 31, 1885, No. 4,060,) to of which the following is a specification.

Our invention relates to that class of presses known as "link-presses," wherein a toggle or link is employed.

The press herein described is primarily designed for use in the manufacture of earthenware; and the principal object of our invention is to provide means whereby the movement of the ram, and consequently the amount of pressure on the article being molded, may 20 be regulated.

In the drawing which serves to illustrate our invention the press is represented in side elevation.

A represents a substantial frame mounted 25 on a base, B.

C is a bracket, fixed by screws or bolts *a a* to the upright of frame A. This bracket has a cap, C', secured to it by screws *b b*, and in the bracket and its cap is formed the guide in 30 which plays the ram D of the press. We have not deemed it necessary to show the mold or die, which is secured to the end of the ram, but removably, so that it may be conveniently removed and replaced.

35 E is the fulcrum of the toggle, which is formed on the end of a screw, E', which passes through the upper part of frame A, and is provided with jam or lock nuts *c c*, whereby the fulcrum may be adjusted and set up or down, as required.

If F are the links of the toggle, coupled, respectively, to the fulcrum E at *x* and to the ram D at *y*.

To the knuckle *z* of the toggle is coupled a 45 connecting-rod, G, the other end of which is coupled to an arm, H, on a rock-shaft, I, mounted in brackets on the frame A.

To the shaft I is secured an operating-lever, J, on the short arm J' of which is adjustably mounted a counterpoise, K, of sufficient weight 50 to raise the ram and balance the other parts. A set-screw, *d*, in the frame A serves to limit the movement in this direction by engaging the arm H. Any stop device may be employed for this purpose. We have broken away the 55 bracket to show the stop-screw *d*.

The fulcrum is adjusted and set up or down by the nuts *c* to suit the work to be done, and when the lever J is depressed it acts through shaft I, arm H, and connecting-rod J to straighten the toggle and depress the ram D. When the links F of the toggle are brought to a straight line, the ram will have reached the extreme point of its downward movement, and any further movement of the lever J will 65 only serve to relieve the pressure by lifting or retracting the ram. Now, by setting the fulcrum E lower down, the ram may be made to move farther down before it begins to lift, and, conversely, by setting the fulcrum higher 70 up, the end or limit of the downward movement of the ram will be correspondingly raised. Thus by means of nuts *c* the limit of the downward travel or movement of the ram may be exactly defined and determined to suit the 75 class of work, and nothing is left to the judgment or discretion of the operator, who may be unskilled.

We do not limit ourselves to the precise construction of the frame-work and parts of 80 our press, as these may be varied somewhat within the knowledge of a skilled workman without departing materially from our invention.

Having thus described our invention, we 85 claim—

1. The combination, with the ram D and its guide, of the fulcrum-screw mounted in the frame of the press, the adjusting-nuts *c c* on said fulcrum-screw, and the links F F, connected together at *z* and to the fulcrum-screw and ram, respectively, at *x* and *y*, all arranged to operate substantially as set forth. 90

2. The combination, with the ram D and its

guide, of the fulcrum-screw mounted in the frame of the press, the adjusting-nuts *c c* on said fulcrum-screw, the links *F F*, connected to said fulcrum-screw and ram, the shaft *I*, 5 provided with an arm, *H*, the rod *G*, connecting arm *H* with the links *F F* at *z*, the operating-lever *J*, attached to shaft *I*, and means for retracting the parts and throwing back said lever, substantially as set forth.

10 In witness whereof we have hereunto signed

our names in the presence of two subscribing witnesses.

FREDERIC GEORGE JOHNSON.
ALFRED JOHNSON.
